DESIGN FOR A COMBINATION SAUCER AND
CREAM PITCHER HOLDER

Edwin J. Zachary, Merced, Calif.

Application February 12, 1946, Serial No. 126,523

Term of patent 3½ years

(Cl. D44—14)

To all whom it may concern:

Be it known that I, Edwin J. Zachary, a citizen of the United States, residing at Merced, in the county of Merced and State of California, have invented a new, original, and ornamental Design for Combination Saucer and Cream Pitcher Holder, of which the following is a specification, reference being had to the accompanying drawing, forming a part thereof.

Fig. 1 is a perspective view of a combination saucer and cream pitcher holder showing my new design.

Fig. 2 is a top plan view of the same.

Fig. 3 is a sectional elevation on line 3—3 of Fig. 2.

I claim:

The ornamental design for a combination saucer and cream pitcher holder as shown.

EDWIN J. ZACHARY.
